CLAIM

The ornamental design for a transfer robot as shown and described.

DESCRIPTION

1. Transfer robot

Reproduction 1.1 is a front view of a transfer robot, showing our new design; reproduction 1.2 is a back view thereof, reproduction 1.3 is a left view thereof; reproduction 1.4 is a right view thereof; reproduction 1.5 is a top view thereof; reproduction 1.6 is a bottom view thereof, reproduction 1.7 is a perspective views thereof.

The lightened part in reproduction 1.6 shown within the broken-line perimeter illustrates portions of the transfer robot that form no part of the claimed design.

1 Claim, 5 Drawing Sheets
